UNITED STATES PATENT OFFICE

101,815

DESIGN FOR A REEL

Ray C. Kivley, Oak Park, Ill., assignor to Western
Electric Company, Incorporated, New York,
N. Y., a corporation of New York

Application April 25, 1936, Serial No. 62,306

Term of patent 14 years

To all whom it may concern:

Be it known that I, Ray C. Kivley, a citizen of
the United States, residing at Oak Park, in the
county of Cook and State of Illinois, have in-
vented a new, original, and ornamental Design
for a Reel, of which the following is a specifica-
tion, reference being had to the accompanying
drawing, forming part thereof, wherein

Fig. 1 is a perspective view of a reel showing
my new design, and

Fig. 2 is a fragmentary elevational view show-
ing the base portion thereof with the shaft broken
away for convenience of illustration.

I claim:

The ornamental design for a reel, as shown and
described.

RAY C. KIVLEY.
